UNITED STATES PATENT OFFICE

JOHN A. GEROW AND ALFRED C. CANNON, OF EL SEGUNDO, CALIFORNIA

FLAGPOLE HOLDER

Application filed August 11, 1928. Serial No. 298,914.

This invention relates to flag pole holders, and particularly to a novel means for securing a band about a pole. In particular the invention contemplates the use of a band adapted to encircle a pole with a quick detachable means to permit the band to separate and likewise to tightly secure said band about the pole when in position of service.

An object of the invention is to provide a 10 clamp so formed and constructed as to permit ready adjustment of a band about an object.

In practicing the invention, we may provide a band adapted to have its ends overlap and which band may be provided with a series 15 of spaced perforations. Clamping means comprising a two-part member is adapted to be secured to the band at any determined position, one of said clamping members being adjustably received within certain of the selected perforations, while the other member 20 of said clamping means is adapted to cooperate with the first member to either tighten the band about an object or to release said band from said object.

25 Other objects include a device of the character stated which is simple of construction, inexpensive to manufacture, and generally superior.

With the above and other objects in view, 30 the invention consists in the novel and useful provision, formation, construction, association, and relative arrangement of parts, members and features, all as shown in a certain embodiment in the accompanying drawing, described generally, and more particularly 35 pointed out in the claims.

In the drawing:

Figure 1 is an elevation of a flag pole holder incorporating the invention, said flag pole 40 holder being mounted upon a pole, such as an electric light pole or the like,

Figure 2 is an enlarged detail of the improved clamping means,

Figures 3 and 4 are sectional views on an 45 enlarged scale and showing the clamping means in open and closed positions, respectively, and

Figure 5 illustrates the clamping means in open position.

50 Referring now with particularity to the

drawing, the pole such as an electric light pole, is designated by A, and the improved clamping means by B. The clamping means B is adapted to cooperate with a band a. This band is adapted to encircle the pole A 55 with the ends thereof normally overlapping, as illustrated in Figures 3, 4, and 5, and which band is provided with a plurality of transverse spaced perforations 1. A flag pole bracket b which includes a segmental 60 plate 2 is provided with one or more outstanding studs 3. A loop 4 and a socket 5 may be utilized in conjunction with the bracket b. As shown, the flag pole 6 is received through the loop and within the 65 socket 5, whereby the flag pole is held at an angularity relative to the pole A. It is quite obvious that the position of said bracket b relative to the pole A can be regulated in accordance with the position of the 70 studs 3 relative to the band a, and particularly the perforations 1 of said band. After the selected number of brackets b have been placed in position of adjustment relative to said band, the clamping means B may be 75 brought into operation. This clamping means B comprises two member c and d, the member c including a plate which is secured in any suitable manner, such as by 80 passing studs through certain perforations in the band, as indicated at 7 and 8, and then topping or up-setting said stubs. This plate c is provided with a bifurcated extremity 9, and each furcation has an enlarged 85 end 10 which is transversely bored to receive a pin between such enlarged ends and which pin carries a lever 11. This lever is 90 provided with a curved cam head 12. The member d includes a plate, one end of which is offset, as shown at 15, whereby such end at the offset portion may be passed through one of the perforations 1 of the band so that the said plate will have parts thereof lying on both sides of said band a. Such 95 plate is likewise provided with a stud 16 adapted to be received in one of the perforations of the band. A curved head 17 is provided on the plate d which curved head is adapted to cooperate with the cam head 100 12 of the lever.

The operation of the invention is as follows:

If we assume that the band *a* is placed about the pole *A* with the various flag pole bracket carriers *b* in position relative to said band, the plate *d* is placed within certain perforations of the band whereby the band is fairly tight when the lever *11* is in its outward position as illustrated in Figure 3. 10 When in this position, the band *a* may be pushed downwardly relative to the pole *A* to say the dotted line position of Figure 1, whereupon the lever *11* may be revolved to the position shown in Figure 4, it being evident that the cam head will draw said band *a* tightly about the pole *A*.

It is obvious that the invention may be used for many purposes other than that illustrated; for instance—for clamping hose for use with radiators, couplings, and the like; and that modifications may be made in the invention in departure from the particular description and the drawing without, however, departing from the true spirit of 25 the invention.

Having thus disclosed our invention, what we claim and desire to secure by letters patent is:

1. In a clamp, a plate having a curved 30 head and an offset end for securing the plate to an object and a second plate provided with a cam-headed lever adapted to cooperate with the curved head of the first plate.

2. The combination with a transversely 35 perforated band, of means for securing said band in position of adjustment about an object; said means including two members, the first of said members being provided with a curved head and an offset end portion, said offset end portion being adapted 40 to be passed through one of the perforations of said band whereby said member has portions lying on both sides of the band; said second member being secured to said band 45 and provided with a cam-headed lever, the head portion of which is adapted to cooperate with the curved head of the first member to cause relative movement between said members.

50 3. The combination with a transversely perforated band, of means for securing said band in position of adjustment about an object; said means including a plate having a body portion and an offset end portion, said offset end being adapted to be passed 55 through one of the perforations of said band, whereby said end will lie on one side of the band and the body portion on the opposite side thereof, a stud on said body 60 for entering other of said perforations of the band and whereby the plate is positioned relative to the band; a second plate secured to said band and formed with a bifurcated end, a lever swingingly mounted between 65 said bifurcations, said lever cooperating

with the first plate in such a manner as to cause relative movement therebetween when the lever is moved.

In testimony whereof we have signed out names to this specification at El Segundo, California, this 17th day of April, 1928.

JOHN A. GEROW.
ALFRED C. CANNON.
